UNITED STATES PATENT OFFICE.

GEORGE E. MOLYNEUX, OF BAYONNE, NEW JERSEY, ASSIGNOR TO THE SINGER MANUFACTURING COMPANY, A CORPORATION OF NEW JERSEY.

LOOPER MECHANISM FOR SEWING-MACHINES.

1,127,795.

Specification of Letters Patent.

Patented Feb. 9, 1915.

Application filed February 23, 1910. Serial No. 545,345.

To all whom it may concern:

Be it known that I, GEORGE E. MOLYNEUX, a citizen of the United States, residing at Bayonne, in the county of Hudson and State 5 of New Jersey, have invented certain new and useful Improvements in Looper Mechanism for Sewing-Machines, of which the following is a specification, reference being had therein to the accompanying drawings.

10 This invention relates to an improvement in looper-actuating mechanism for chain-stitch sewing machines more particularly of the class constructed with a cylindrical bed or work-supporting horn and feeding mechanism designed to advance the work longitudinally of the latter, such as is disclosed in my pending application Serial No. 521,801, filed October 9, 1909; and it has for 15 its object to provide an effective simple and compact mechanism for imparting to the looper its endwise loop-seizing and sidewise or needle-avoiding movements.

As preferably constructed, the looper-carrier is pivotally mounted upon a rock-shaft which imparts to the looper through its carrier the endwise loop-seizing and shedding movements, rocking movements being imparted to the looper-carrier to transmit the sidewise looper movements by 20 a connection with a jog-bar, slidably mounted in bearings parallel with the looper rock-shaft and pivotally connected with one end of a gyratory thrust-rod whose opposite end has a pivotal connection with a 25 rotary shaft at a point of the latter at one side of its axis of rotation, which axis is also offset from the point of connection of the thrust-rod with the jog-bar. The rotation of the shaft obviously causes the thrust-rod to assume different angular relations with the jog-bar to which it thus imparts endwise jogging movements. A bushing provided with an eccentric bore affords a bearing for the jog-bar, so that the circular 30 adjustment of the bushing acts to vary the degree in which the jog-bar is offset from the axis of its actuating rotary shaft, thereby correspondingly adjusting the amplitude of its jogging movements.

35 In the drawings, Figure 1 is a transverse sectional elevation of the forward portion of the cylinder-bed machine of my said pending application, with the needle and presser-foot and the lower portions of their carrying bars, and Fig. 2 a front end view

of the same with the end-cap of the cylinder-bed removed. Fig. 3 is a perspective view of the looper and its carrier. Fig. 4 is a plan of the jogging means for producing the needle-avoiding movements of the 60 looper. Fig. 5 is a perspective view of a portion of the looper-jogging means, and Figs. 6 and 7 sectional side and end elevations of the bushing for the jog-bar. Fig. 8 is an enlarged perspective view, partly in 65 section, representing a member of the looper-jogging mechanism. Fig. 9 is a sectional side elevation of a sewing machine embodying certain of the characteristic features of the present invention, and repre- 70 senting a slight modification of the looper mechanism; and Fig. 10 is a rear end view of the same with the base and bracket-arm standard in section.

Referring to Figs. 1 to 8 inclusive, the 75 cylinder-bed or work-supporting horn 1 is provided with the throat-plate 2 and the removable end-cap 3 housing the looper and its carrier. Mounted axially of the arm 1 in the bearing member 4 thereof is a longi- 80 tudinally extending looper rock-shaft 5 which derives its rocking movements from any suitable actuating means, as, for instance those shown in Figs. 9 and 10 of the drawings hereof. The looper-supporting 85 shaft has mounted upon its forward end the split collar 6 secured adjustably thereon by means of the clamp-screws 7 passing through spaced lateral ears 8 of said collar. The collar 6 is formed with a forwardly 90 projecting stud 9 of angular cross-section with parallel sides and formed with a transverse fulcrum-pin aperture 10 intersected by the axial screw-hole 11.

Pivotally mounted upon the transverse 95 fulcrum-pin 12 passing through the aperture 10 of the stud 9 is the looper-carrier 13 which is formed with a rectangular aperture 14 fitted to the sides of and embracing the stud 9. The fulcrum-pin 12 is flattened 100 intermediate its ends at 12^x where it is engaged by the point of the set-screw 15 entering the aperture 11 of the stud 9 to secure the fulcrum-pin against displacement. The looper comprises the blade 16 formed with 105 the eyes 17 connected by the usual thread-groove and provided with a shank 18 with angularly arranged portion 19 secured by means of the set-screw 20 within a socket in the carrier 13. The looper-blade is ar- 110

ranged transversely of the supporting shaft 5 and parallel with the fulcrum-pin 12 upon which its carrier is mounted.

The body of the looper-carrier beneath the fulcrum-pin 12 is split in a plane parallel with said pin and provided in its lower portion with a segmental raceway 21 afforded by the lateral wings 22 which are formed with transverse screw-holes entered by the clamp-screws 23 by which said wings may be relatively adjusted to take up wear. Arranged within the raceway 21 beneath the axis of the looper-shaft 5 is a wearing block composed of two separable parts 24 and 25, the former being provided with steady pins 26 entering apertures 27 in the latter, and both being provided with portions of a spherical socket 28 embracing the head 29 of a ball-stud 30 whose shank is 20 clamped by means of the screw 31 in a vertical socket in the forwardly projecting arm 32 of a split collar 33 clamped by means of a screw 34 upon the reduced forward end 35 of the reciprocating plug or jog-bar 36 25 arranged parallel with and beneath the looper rock-shaft 5.

The jog-bar 36 is fitted within the eccentric bore or bearing aperture 37 of the cylindrical bushing 38 which is in turn mounted 30 within a cylindrical aperture 39 of the bearing member 4 in which the looper-shaft is journaled. The bushing 38 is adapted to be turned within its aperture 39 to change the position of the jog-bar 36 laterally, but is 35 normally secured against shifting by engagement with the annular external groove 40 therein of the point of a set-screw 41 introduced through a transverse aperture 42 in the wall of the horn 1. The bushing is 40 shown in Figs. 6 and 7 provided with an internal annular oil cavity 43 and with a longitudinal keyway 44 to receive the spline or feather 45 of the jog-bar 36 by which the latter is prevented from turning in the 45 bushing. As the circular adjustment of the bushing 38 operates to change the level of the arm 32, it is evident that the ball-stud 30 may be adjusted to compensate therefor by loosening the clamp-screw 31.

50 The looper-carrier 13 may also be adjusted both longitudinally and circularly upon its supporting rock-shaft or looper support 5 by loosening the clamp-screw 7 of the collar 6 and shifting the same as required, the several adjustments above described serving to properly locate the loop-seizing position of the looper point relatively to the needle, as well as to insure the required lateral throw of the looper in performing its needle-avoiding movements.

55 The rearward end portion of the reciprocating plug or jog-bar 36 is formed with a removable lateral section 46 secured in position by means of the screw 47, and partly 60 within this removable section and partly

within the adjacent portion of the jog-bar is axially disposed a spherical socket 48 with a flaring rearwardly extending opening entered by the reduced forward portion of the gyroscopic thrust-rod 49 terminating at its extremity in the ball 50 fitted within said cavity. The similarly formed opposite end of the thrust-rod is correspondingly reduced and provided with a ball 51 fitted within a similar cavity or socket 52 formed partly in the disk 53 and partly within a removable peripheral section 54 thereof secured in place by means of screws 55. The socket 52 is laterally offset from the center of the disk 53, which latter is fixed upon the forward end of a rotary shaft 56 journaled in the bearing member 57 of the work-supporting horn 1. This rotary shaft is or may be an extension of the main-shaft to which power is transmitted from any suitable source. 85

As herein represented, the machine is provided with a reciprocating needle-bar 58 carrying the needle-clamp 59 in which are secured by means of clamp-screws 60 the shanks of two eye-pointed needles 61 with which the single looper cooperates in the production of stitches. The machine is also provided with the usual presser-bar 62 to the reduced lower end of which is secured the shank 63 of the hinged presser-foot 64 normally resting upon the throat-plate 2 and opposed to the serrated operative face of the feed-dog 65 which is secured by means of the screw 66 upon a block 67 at the forward end of the longitudinally reciprocating feed-bar 68, which is formed with a necked portion 69 fitted within the tilting bearing sleeve 70 which is in turn pivotally mounted by means of center-screws 71 upon the yoked upper end of the post or standard 105 72 provided at its lower end with a strap 73 embracing a feed-lifting eccentric 74 whose hub 75 is secured by means of set-screws 76 upon the rotary shaft 56. It will thus be seen that the feed-dog 65 has feeding movements longitudinally of the work-supporting horn transversely of the endwise loop-seizing movements of the looper-blade 16, being prevented from lateral movement by means of a guideway 4^x of the bearing member 4 in which the sides of the block 67 are fitted and the feed dog is supported by and receives its rising and falling movements from the eccentric 74 upon the rotary looper-jogging shaft 56. 110

120 Referring now more particularly to Figs. 9 and 10, the machine frame is shown formed with the hollow base 1^x from which extends the cylinder-bed or horn 1 and overhanging bracket-arm 1^y in the head of which latter are journaled the reciprocating needle-bar 58 and the presser-bar 62. The base has the rearward bearing-boss 77 containing the bushing 78 in which is journaled the rear end of the main-shaft 56 fitted within the 125 130

bearing member 79 at the rearward end of the cylindrical-bed 1.

The bracket-arm is provided at its rearward end with a bearing-boss 80 in which is journaled the rearward end of the needle-actuating rock-shaft 81 whose forward end is fitted to and passes through the bearing member 82 into the cavity of the head of the bracket-arm, where it is provided with the usual crank-arm 83 carrying a pin 84 connected by means of the pitman 85 with a lateral pin upon the collar 86 fixed upon the needle-bar 58. Upon the rearward end of the rock-shaft 81 is fixed the lateral crank-arm 87 which carries the stud 88 embraced by the upper end of a pitman 89 whose lower end embraces a crank 90 formed in the main-shaft 56 and adapted to communicate through the described connecting mechanism reciprocating movements to the needle-bar and needles.

The needle-actuating rock-shaft has fixed thereon, at the opposite side of the bearing-boss 80 from the crank-arm 87, a second lateral crank-arm 91 carrying a screw-stud 92 embraced by the upper end of the pitman-rod 93 whose lower end embraces a screw-stud 94 intermediate the ends of a vibrating lever 95 having one end journaled upon the fixed fulcrum-pin 96 sustained by a lug 96^x upon the base 1^x. The outer end of the lever 95 carries a screw-pin 97 connected by means of a link 98 with a similar pin 99 carried by a crank-arm 100 fixed upon the rearward end of the looper rock-shaft 5.

The component members of the operative connections between the needle-actuating and looper rock-shafts are so arranged and proportioned that the rocking of the former through its crank-and-pitman connections with the actuating crank 90 of the main-shaft causes the screw-pin 97 to move into and out of alignment with the fulcrum-pin 96 and crank-pin 99 of the crank-arm 100 in imparting each complete reciprocation of the needle, whereby the looper rock-shaft receives a dwell in the production of each stitch as the needles attain their highest position and begin their descent for a succeeding stitch.

As represented in Fig. 9, the looper derives its operative endwise loop-seizing and shedding movements from its supporting rock-shaft 5, and its sidewise or needle-avoiding movements are imparted to it by means of an actuating cam 101 secured upon the forward end of the reduced forward portion of the main-shaft 56 and provided with a peripheral cam-groove 102 entered by the roller-stud 103 upon the forward projecting arm 104 of a collar 105 secured by means of the set-screw 106 upon the rearward end of the jog-bar 36 connected with the looper-carrier as described in connection with the preceding figures.

By the employment of the jog-bar 36 in alignment, or substantially so, with the main-shaft disposed in the lower side of the cylinder-bed, the parts may be arranged very compactly, so as to provide for a cylindrical work-support of smaller diameter for accommodation of hollow articles of the smaller sizes, such as sleeves of children's garments, for which the present improvement is more particularly designed, although 76 adapted for many other classes of work. In both of the described forms of the improvement, the movements of the jog-bar 36 are so timed that while the needle is approaching and beginning its recession from 80 its highest position, and the looper is on the dwell of its endwise travel, a sidewise needle-avoiding movement takes place simultaneously with and in opposition to the operative work-advancing movement of the 85 feed-dog, thereby insuring the drawing of the looper-thread taut preparatory to the descent of the needles within the distended looper-thread loop leading from the needle-hole in the throat-plate to the looper-eye 90 and thence backwardly along the looper-blade. In practice, any usual or suitable mechanism may be employed for manipulating the looper-thread and taking up slack in the same preparatory to the descent of the 95 needles, but the described reciprocal movements of the looper and the work preparatory to the descent of the needles insures against the catching of the looper-thread upon the needle points or the skipping of 100 stitches.

As will be seen by reference more particularly to Fig. 4, the spherical end 51 of the gyroscopic thrust-rod 49 moves in a circular path which is divided by the horizontal 105 plane of the axis of the jog-bar 36 into longer and shorter arcs. The operative reciprocal movements of the jog-bar are performed during the traverse of the extremity 51 of the member 49 in the longer 110 of these arcs and mainly in the travel toward and from the portion thereof farthest from said plane. As the direction of movement of the thrust-rod extremity 51 in the smaller arc is nearly parallel with said 115 plane, the slight endwise retractive movement transmitted by the thrust-rod to the jog-bar is practically inappreciable during such traverse and a dwell is produced in the rocking movement of the looper-carrier. A 120 similar condition exists, but in less degree because of the inclination of the thrust-rod, when the spherical extremity 51 of the latter moves through the portion of the larger arc farthest removed from the plane referred to, thereby producing another dwell. While in theory this accelerated-motion mechanism does not entirely interrupt the rocking movements of the looper-carrier upon its pivotal supporting pin 12, in practice these 130

rocking movements of the looper-carrier are during the periods of dwell so small as to be inappreciable for a considerable portion of each revolution of the main-shaft. Substantially the same timing of the rocking movements of the looper is produced by the employment of the cam 101 for imparting to the jog-bar its reciprocatory movements.

By the provision of accelerated-motion actuating mechanism for imparting both the endwise and sidewise movements to the looper-blade, and so timing these devices that they impart the respective looper movements alternately, the looper is caused to move in a path which is not elliptical, as has been usual heretofore, but in a substantially rectangular path, whereby the looper is permitted to move in substantially parallel planes upon opposite sides of the needle-paths in performing its loop-seizing and loop-shedding movements so as to coöperate with precision with the two needles arranged side-by-side, while it is permitted to move in a substantially short path and its length is correspondingly short as compared with that of loopers heretofore employed in this class of mechanism. The sidewise movements of the looper are therefore interrupted during the initial advance and receding endwise movements for seizure of the needle-thread loops and presentation of loops of its thread for entrance of the needles. The looper is thus caused to coöperate with equal precision with each of the spaced needles in a manner which has not been attained heretofore with a looper moving in a substantially elliptical path in which its blade moves at different distances from the spaced needles with which it coöperates.

As will be seen by reference to Figs. 1, 2 and 9, the looper rock-shaft is mounted concentrically with the cylinder-bed, so that the endwise movements of the looper-blade, which is formed concentrically therewith, are in a circular arc, and the cylinder-bed may therefore be made of minimum size for housing its several operative parts without extra clearance to accommodate the looper movements. The pivotal support of the looper-carrier intermediate its upper and lower ends also and the connection of its jogging mechanism therewith below said support produces a balance of the loop-taking member which is conducive to the high speed for which the machine is designed, without noise and excessive wear of the parts.

The rearward end of the feed-bar 68 carries a strap 68^x embracing a ball-stud 107 upon a lateral arm 108 of a rocking sleeve 109 mounted upon a vertical fulcrum-stud 110 and provided with a lateral arm 111 having a suitable pitman connection, including the strap 112, with the actuating eccentric 113 upon the main-shaft.

The thread-controlling parts are in practice so timed that the needle-threads are slackened as the needles begin to descend until their eyes have passed beneath the work, but are thereafter drawn up; and the preceding stitches are finally set as the needles reach their lowest position, the lower thread being slack at this time to permit the lower-thread loop to be readily drawn into place beneath the fabric. As the needles begin to rise to present their loops to the looper, the needle-threads are again slackened while their loops are entered by the looper, but as the needle-bar reaches its highest position the needle-threads are tightened so as to draw a sufficient supply of needle-thread for the succeeding stitch formation.

The looper mechanism is so timed in its operation that the needle-avoiding motion of the looper is completed simultaneously with the feeding action for advancing the work just as the needles assume their extreme upper positions and the looper its extreme advance position with the needle-thread loops upon its blade. As the needles descend with their points about to enter the work, the looper begins its retrograde or loop-shedding movement with its thread maintained taut until the points of the needles descend below the looper-thread intermediate the needle-holes of the throat-plate and the eye in the looper point. While the needles are descending to extreme lower position, the looper continues its retrograde movement until its point is beyond the farthest needle, when the quick sidewise or needle-avoiding movement takes place so as to bring the loop of the needle-thread from the looper point directly to the needle-hole, when the arrival of the needles at extreme lower position effects the setting of the stitch and the drawing of sufficient looper-thread for the purpose freely through the looper from the lower thread-supply. As the needles begin to rise, the looper commences its advance or loop-seizing movement, which is completed as the needles reach their extreme upper positions.

It is evident that other means than those disclosed herein may be readily devised for varying the degree of operative movement of the gyratory thrust-rod 49 without departing from the present invention. It is also evident that the present improvement is susceptible of considerable modification in other respects without departure from the scope of the invention.

Having thus set forth the nature of the invention, what I claim herein is:

1. In a sewing machine, the combination with the frame constructed with a hollow standard and a cylindrical work-supporting arm extending laterally therefrom, a rotary shaft extending across said hollow

standard and through a portion of the length of said work-supporting arm, and a reciprocating needle, of a rock-shaft mounted within and in axial relation with said work-supporting arm, a looper-carrier having a transverse pivotal connection with and supported upon said rock-shaft, a looper mounted in said looper-carrier with its blade disposed transversely of said shaft, means connected with said rotary shaft within the hollow standard for actuating said rock-shaft, a reciprocating member disposed within the work-supporting arm in advance of and substantially parallel with said rotary shaft, an operative connection between said reciprocating member and the rotary shaft, and a connection between said reciprocating member and the looper-carrier for rocking the latter upon its supporting rock-shaft.

2. In a sewing machine, the combination with a reciprocating needle, of a rock-shaft mounted in fixed bearings, a looper-carrier having a transverse pivotal connection therewith by which it is supported thereon and provided with a segmental raceway, a looper mounted in said looper-carrier with its blade disposed transversely of said shaft, means for rocking said shaft, and means, including a reciprocating rod parallel with said shaft and provided with a stud entering the raceway of said looper-carrier, for rocking said looper upon said shaft.

3. In a sewing machine, the combination with the frame constructed with a cylindrical work-supporting arm, and a reciprocating needle, of a rotary shaft and a looper-supporting rock-shaft substantially parallel therewith mounted within and longitudinally of said arm, an eyed looper mounted on said rock-shaft, a feed-bar mounted within and longitudinally of said arm and carrying a feed-dog, independent connections between said feed-bar and said rotary shaft disposed respectively within and exterior to said arm for imparting endwise and vibratory movements to the feed-bar, a connection between the looper-supporting shaft and said rotary shaft exterior to said arm for imparting loop-seizing movements to the looper, and a connection between said shaft and the looper arranged within said arm and independent of the looper-supporting shaft connection for imparting sidewise or needle-avoiding movements to the looper.

4. In a sewing machine, the combination with a reciprocating needle, of a rock-shaft, a looper-carrier fulcrumed thereon and provided with a segmental raceway transverse to said shaft, a looper mounted in said looper-carrier, a rotary shaft parallel with said rock-shaft, a reciprocating bar also parallel with said rock-shaft, an actuating connection between said rotary shaft and reciprocating bar, a socketed wearing block fitted

to the raceway in said looper-carrier, and a ball-stud carried by said reciprocating bar and fitted within the socket of said wearing block.

5. In a sewing machine, the combination with a reciprocating needle, of a rock-shaft, a looper-carrier fulcrumed thereon and provided with a longitudinally split segmental raceway and means to adjust the side walls of said raceway relative to each other, a looper mounted in said looper-carrier, a rotary shaft parallel with said rock-shaft, a reciprocating bar also parallel with said rock-shaft, an actuating connection between said rotary shaft and reciprocating bar, a socketed wearing block fitted to the raceway in said looper-carrier, and a ball-stud carried by said reciprocating rod and fitted within the socket of said wearing block.

6. In a sewing machine, the combination with a cylinder-bed or horn, of a reciprocating needle-bar provided with a needle, a rock-shaft journaled within and longitudinally of said cylinder-bed or horn, a looper-carrier movably mounted upon and adjustable both circularly and longitudinally of the same, means for imparting sidewise movements to said looper upon and relative to its supporting shaft, and a cap applied to the extremity of said cylinder-bed or horn and housing said looper within the same.

7. In a sewing machine, the combination with a reciprocating needle, of a rock-shaft, a collar mounted upon said rock-shaft and provided with an angular portion having parallel sides, a looper-carrier apertured to embrace the angular portion of said collar, a pivotal pin extended through the looper-carrier and collar transversely of the latter, a looper mounted in said looper-carrier above its pivotal pin, and means connected with the looper-carrier below said pivotal pin for rocking said looper on the rock-shaft.

8. In a sewing machine, the combination with the frame comprising a cylindrical work-supporting arm, of a needle, a looper, a looper-carrier, a movable support for said carrier disposed within and longitudinally of said arm and adapted to transmit operative movements in one direction to the looper, and upon which support the looper-carrier is movably mounted, a jogging member, an operative connection between said jogging member and the looper-carrier whereby movements are imparted to the looper transversely of those first-named, a rotary shaft disposed within and longitudinally of the work-supporting arm, and a thrust-rod pivotally connected at its ends respectively with said jogging member and the rotary shaft at points offset from the axis of the latter.

9. In a sewing machine, the combination with a needle, of a looper having a blade, a

looper-carrier upon which the same is mounted, a supporting rock-shaft, a fulcrum-pin for said looper-carrier sustained upon the rock-shaft transversely of its axis 5 in a plane parallel with the looper-blade, a jog-bar, an operative connection between said jog-bar and the looper-carrier for imparting to the latter rocking movements upon its fulcrum-pin, a rotary shaft parallel with the rock-shaft, and a thrust-rod connected at the ends respectively with said bar and said shaft at points offset from the latter's axis.

10. In a sewing machine, the combination with a needle, of a looper having a blade, a looper-carrier upon which the same is mounted, a supporting rock-shaft, a fulcrum-pin for said looper-carrier sustained upon the rock-shaft transversely of its axis 15 in a plane parallel with the looper-blade, a jog-bar, a bearing for said jog-bar affording means for lateral adjustment thereof, an operative connection between said jog-bar and the looper-carrier for imparting to the latter rocking movements upon its fulcrum-pin, a rotary shaft parallel with the rock-shaft and in eccentric relation to the jog-bar, and a thrust-rod connected at the ends respectively with said bar and said shaft at 20 points offset from the latter's axis.

11. In a sewing machine, the combination with a needle, of a looper having a blade, a looper-carrier upon which the same is mounted, a supporting rock-shaft, a fulcrum-pin for said looper-carrier sustained upon the rock-shaft transversely of its axis 25 in a plane parallel with the looper-blade, a jog-bar, a bushing mounted for circular adjustment within a fixed support and provided with an eccentric bearing aperture to which said jog-bar is slidingly fitted, an operative connection between said jog-bar and the looper-carrier for imparting to the latter rocking movements upon its fulcrum-pin, a rotary shaft parallel with the rock-shaft, and a thrust-rod connected at the ends respectively with said bar and said shaft at 30 points offset from the latter's axis.

12. In a sewing machine, the combination with the frame comprising a cylindrical work-supporting arm, of a needle, a looper, a looper-carrier, a movable support for said carrier disposed within and longitudinally of said arm and adapted to transmit operative movements in one direction to the looper, and upon which support the looper-carrier is movably mounted, a jogging member, an operative connection between said jogging member and the looper-carrier 55 whereby movements are imparted to the looper transversely of those first-named, a rotary shaft disposed within and longitudinally of the work-supporting arm, a thrust-rod pivotally connected at its ends respectively with said jogging member and the 60

rotary shaft at points offset from the axis of the latter, a feed-dog, a feed-bar movable longitudinally of the work-supporting arm, and a support for said feed-bar sustained upon said shaft.

13. In a sewing machine, the combination with the frame comprising a cylindrical work-supporting arm, of a needle, a looper, a looper-carrier, a movable support for said carrier disposed within and longitudinally of said arm and adapted to transmit operative movements in one direction to the looper, and upon which support the looper-carrier is movably mounted, a jogging member, an operative connection between said jogging member and the looper-carrier whereby movements are imparted to the looper transversely of those first-named, a rotary shaft disposed within and longitudinally of the work-supporting arm, a thrust-rod pivotally connected at its ends respectively with said jogging member and the rotary shaft at points offset from the axis of the latter, a feed-dog, a feed-bar movable longitudinally of the work-supporting arm, a feed-lifting eccentric upon said shaft, and a feed-bar support provided with a strap embracing said eccentric.

14. In a sewing machine, the combination with the frame constructed with a cylindrical work-supporting arm, and a reciprocating needle, of a rock-shaft mounted within and in axial relation to said work-supporting arm, a looper-carrier having a transverse pivotal connection with and supported upon said rock-shaft, an eyed looper mounted in said looper-carrier with its blade disposed transversely of said shaft, means exterior to the work-supporting arm for rocking said shaft, and means disposed within said work-supporting arm and independent of said rocking means for rocking the looper-carrier upon its pivotal connection with said shaft.

15. In a sewing machine, the combination with a reciprocating needle, of a rock-shaft mounted in fixed bearings, a looper-carrier having a transverse pivotal connection with and supported by said rock-shaft, an eyed looper mounted in said looper-carrier with its blade disposed transversely of said shaft, actuating mechanism for said rock-shaft including means for producing a dwell thereof in extreme position, and actuating mechanism for rocking the looper-carrier upon its pivotal connection with said shaft including means for producing a dwell of the looper-carrier in extreme position, said actuating means being timed to operate alternately.

16. A looper mechanism including in combination a rotating shaft, a rocking looper-support substantially parallel with said shaft, a looper carried thereby, means for giving said looper a loop-taking movement

- crosswise of said shaft, and means for giving said looper a sidewise or needle-avoiding movement endwise of said shaft, said last-named means including a member carried 5 at the outer end of said shaft, a link inclined to the axis of said shaft and having a universal-joint connection with said member at a point at one side of the axis of said shaft, and means for connecting the outer 10 end of said link to said looper at a point at one side of the axis of said shaft, whereby said link will be given a gyratory and endwise movement and thereby impart the sidewise movement to said looper.
- 15 17. A sewing machine including, in combination, a work-support, a rotating shaft extending longitudinally of said work-support, a looper-support substantially parallel with said shaft, a looper mounted thereon 20 between the end of said shaft and the end of the work-support, means for giving said looper a loop-taking movement in a direction transversely of said work-support, and means for giving said looper a sidewise or 25 needle-avoiding movement longitudinally of said work-support, said last named means including a member carried at the end of said shaft, a link inclined to the axis of said shaft and having a universal-joint connection with said member at a point at one side of the axis of said shaft, and means for connecting the outer end of said link to the said looper, the outer end of said link being disposed at one side of the axis of said shaft, 30 whereby said link will be given a gyratory and endwise movement and thereby impart the sidewise movement to said looper.
- 35 18. In a sewing machine, a laterally closed casing, two parallel shafts extending longitudinally thereof, a looper sustained upon and deriving rocking movements from and crosswise of one of said shafts in advance of the extremity of the other, a crank element carried by the extremity of the other 40 shaft, and a pitman attached at one end to said crank element and having its other end connected with said looper and confined to a path of movement at one side of the axis of the second-named shaft, whereby movements lengthwise of said shafts are imparted to said looper.
- 45 19. In a sewing machine, the combination with the frame constructed with a cylinder work-supporting arm, and a reciprocating needle, of a rotary shaft journaled within and extending longitudinally of said arm, a rock-shaft mounted in fixed bearings within said arm parallel with said rotary shaft, a looper mounted upon said rock-shaft with its blade disposed transversely thereto and movable endwise of said shaft, means for imparting operative movements to said rock-shaft, and means for imparting to the looper movements in a direction crosswise of its blade and comprising a crank 55 fixed upon said rotary shaft, a reciprocatory element connected with said looper, and a link having at one end a universal-joint connection with said crank and at the other end a connection with said reciprocatory element disposed eccentrically to the axis of said rotary shaft.
- 60 20. In a sewing machine, in combination, a rotary shaft, a reciprocating needle, a rock-shaft, a looper mounted thereon, actuating means connected with said rotary shaft whereby operative loop-taking movements are imparted to the looper, means connected with the looper independently of said rock-shaft and of said actuating means for imparting sidewise or needle-avoiding movements to the looper, and means for varying the amplitude of said sidewise movements.
- 65 21. In a sewing machine, in combination, a rotary shaft a reciprocating needle, a rock-shaft, a looper mounted thereon, actuating means connected with said rotary shaft whereby operative loop-taking movements are imparted to the looper, and means for imparting to the looper sidewise needle-avoiding movements and comprising a rectilinearly reciprocating rod operatively connected with the looper independently of said actuating means, an operative connection between said rod and the rotary shaft, 70 and adjusting means whereby the action of said connection upon the reciprocating rod may be changed.
- 75 22. In testimony whereof, I have signed my name to this specification, in the presence of 100 two subscribing witnesses.
- GEORGE E. MOLYNEUX.
- Witnesses:
- HENRY J. MILLER,
H. A. KORNEMANN, Jr.
